UNITED STATES PATENT OFFICE.

TOMASZ M. ZAMULEWICZ, OF CHICAGO, ILLINOIS.

ADJUSTABLE SPRING-MOTOR FAN.

1,175,213.

Specification of Letters Patent. Patented Mar. 14, 1916.

Application filed June 29, 1915. Serial No. 36,997.

To all whom it may concern:

Be it known that I, TOMASZ M. ZAMULEWICZ, a subject of the Czar of Russia, residing at Chicago, in the county of Cook and State of Illinois, have invented certain new and useful Improvements in Adjustable Spring-Motor Fans, of which the following is a specification.

This invention relates to certain new and useful improvements in adjustable spring motor fans.

The primary object of the invention is the provision of an air circulating fan adjustable in its position and having a spring motor for actuating the same.

A further object of the device is to provide a spring motor operated rotary fan that is easy to manufacture and inexpensive to maintain, the same being readily adjustable to different levels of operation.

A still further object is to provide a support for maintaining a spring motor operatively geared with a vertically adjustable revolving fan.

With these general objects in view and others that will appear as the nature of the invention is better understood, the same consists in the novel construction, combination and arrangement of parts hereinafter more fully described, illustrated in the accompanying drawings and pointed out in the appended claims.

In the drawings forming a part of this application and in which like designating characters refer to corresponding parts throughout the several views:—Figure 1 is a side elevational view of the device. Fig. 2 is a front elevation thereof with the fan shaft shown in vertical section and the guard thereof removed. Fig. 3 is a vertical longitudinal sectional view of the device looking in the direction of the fan. Figs. 4 and 5 are enlarged horizontal detail views taken upon lines IV—IV and V—V respectively, of Fig. 3, and Fig. 6 is a vertical sectional view taken upon line VI—VI of Fig. 1.

It will be first noted that the invention broadly consists of a mounting support 10 for a spring motor 11 and a vertically adjustable fan 12 operatively connected to the said motor. The said mounting support 10 consists of a rectangular frame 13 positioned upright upon a base 14 while the forward side

15 of the said frame is provided with a longitudinally-arranged dove-tail slot 16. The winding shaft 17 of the spring or motor 11 is journaled transversely through the opposite sides of the frame 13 in the lower portion thereof and in a plane below the front side slot 16. An operating knob or key 18 is carried by the rearwardly-projecting end of the motor shaft 17 and by means of which the said shaft may be turned by the hand of the operator during the winding operation while a dog 19 pivoted to the said frame normally engages a toothed wheel 20 secured to the said shaft whereby the spring is retained under tension when desired. A gear 21 is secured to the shaft 17 and is in constant mesh with a relatively smaller pinion 22 secured to a transverse shaft 23 journaled in the said frame. A plurality of speed increasing relatively large and small pulleys 24 and 25 are operatively positioned between the said shaft 23 and the driven shaft 26, which latter is journaled adjacent the top of the frame 13 while connecting belts 27 connect the pairs of pulleys 24 and 25. The said driven shaft 26 is journaled in a bushing 28 at the rear side of the frame 13 and in a web 29 carried by the front wall 15, which web spans the slot 16 adjacent its inner face.

A mounting block 30 is slidably mounted within the front slot 16 of the frame having a dove-tailed connection therewith as best illustrated in Fig. 5 of the drawings, set screws 31 being carried by the said block for engaging the frame side 15 to retain the said block at the desired elevated adjustment. A stub or fan shaft 32 is horizontally journaled in the said block 30 and has a sprocket wheel 33 secured thereto while the fan 12 is secured to the said stub shaft 32 at the outer end thereof. A protecting guard 34 preferably formed of wire is arranged around the fan 12 and is secured at opposite points 35 upon the outer face of the block 30. A stub shaft 36 is journaled in a boss 37 carried by the front side 15 adjacent the lower end of the slot 16 and has an idler sprocket wheel 38 secured thereon. A sprocket chain 39 runs over the said sprocket wheel 38 and a similar sprocket wheel 40 secured to the aforementioned driven shaft 26 and the said chain is in operative mesh with the oppo-

site sides of the sprocket wheel 33 of the fan shaft 32. The top cross-piece 41 of the frame 13 being removable, the block 30 is slidably inserted within the front slot 16 5 prior to the positioning of the said cross-piece and also prior to the journaling of the driven shaft 26 through the front wall web 29.

With the device set up for use as herein 10 illustrated, it will be seen that the spring 11 may be placed under tension by turning the knob 18 and when desired for use, the dog 19 is pivotally moved out of engagement with the wheel 26 whereupon the force 15 of the spring motor in its unwinding operation turns the gear 21 and the shaft 23 while the driven shaft 26 is revolved with increased rapidity by means of the train of pulleys 24, 25 operatively connecting the 20 said shafts. The sprocket wheel 40 turns during revolution of the driven shaft 26 whereby the sprocket wheel 33 is operated for revolving the shaft 12, it being apparent that the said fan will continue its revolutions until the motor 11 has run down and 25 the power thereof has become exhausted.

The fan 12 may be vertically adjusted as 30 desired by releasing the set screws 31 and forcibly moving the block 30 longitudinally of the slot 16, whereupon the set screws 31 may be again tightened, thus positioning the fan at the desired elevation. It will be seen that this vertical adjustment of the block 30 will be impossible while the 35 sprocket wheel 33 is in operative mesh with the chain 39 unless the chain is shifted during such movement of the block, and this will allow the sprocket wheel 33 to revolve during such vertical adjustment. The 40 parallel engaging portions of the sprocket chain 39 may however, be sufficiently sprung apart to disengage the same from the sprocket wheel 33 thus allowing a free vertical movement of the sprocket wheel 33 and 45 its adjustable mounting block.

A radially movable serviceable ventilating fan is thus arranged which is inexpensive to operate by reason of the spring motor employed and the same is rendered especially 50 advantageous as the plane of the air draft is readily regulated without shifting the entire device.

While the form of the invention herein shown and described is what is believed to 55 be preferable embodiment thereof, it is nevertheless to be understood that various forms, modifications and arrangements of the parts may be made without departing

from the spirit and scope of the invention as set forth in the appended claims.

60

What I claim as new is:—

1. A device of the class described, comprising a rectangular upright frame having a dove-tailed slot in the front side thereof, a block having slidable dove-tail connection with the said slot, positioning means carried by the said block, a fan shaft journaled through the said block, a sprocket wheel and fan secured to the said shaft, a spring motor within the said frame and operative connections between the said motor and sprocket wheel.

65

2. A device of the class described, comprising a rectangular upright frame having a dove-tailed slot in the front side thereof, a block having slidable dove-tail connection with the said slot, positioning means carried by the said block, a fan shaft journaled through the said block, a sprocket wheel and fan secured to the said shaft, a driven shaft journaled in said frame above the said fan shaft, a sprocket wheel upon the outer end of the said driven shaft in alinement with the said fan shaft wheel, an idler sprocket journaled to the said frame beneath the said sprocket wheels, and a sprocket chain operatively carried by the said driven and idler sprockets and operatively meshing with the said fan shaft sprocket at the opposite sides thereof.

70

3. A device of the class described, comprising a rectangular upright frame having a dove-tailed slot in the front side thereof, a block having slidable dove-tail connection with the said slot, positioning means carried by the said block, a fan shaft journaled through the said block, a sprocket wheel and fan secured to the said shaft, a driven shaft journaled in said frame above the said fan shaft, a sprocket wheel upon the outer end of the said driven shaft in alinement with the said fan shaft wheel, an idler sprocket journaled to the said frame beneath the said sprocket wheels, a sprocket chain operatively carried by the 85 said driven and idler sprockets and operatively meshing with the said fan shaft sprocket at the opposite sides thereof, a guard for the said fan positioned between the opposite sides of the said chain and 90 carried by the said block, a spring motor within the said frame, and speed increasing connections between the said motor and driven shaft.

90

In testimony whereof I affix my signature. 115
TOMASZ M. ZAMULEWICZ.
